US00D608705S

(12) **United States Design Patent**
Liu et al.

(10) **Patent No.:** **US D608,705 S**
(45) **Date of Patent:** **** Jan. 26, 2010**

(54) **BRAKE FRICTION PAD**

(75) Inventors: **Weiming Liu**, Windsor (CA); **Rodney J. Silvey**, Cookeville, TN (US); **Jason Heath Mahan**, Lafayette, TN (US)

(73) Assignee: **Federal-Mogul World Wide, Inc.**, Southfield, MI (US)

(**) Term: **14 Years**

(21) Appl. No.: **29/339,403**

(22) Filed: **Jun. 30, 2009**
